UNITED STATES PATENT OFFICE

CARL A. KINNINGER, OF DAYTON, OHIO, ASSIGNOR OF ONE-HALF TO ARTHUR M. KINNINGER, OF DAYTON, OHIO

ANCHOR INSERT

Application filed April 7, 1924. Serial No. 704,669.

My invention relates to concrete construction and more particularly to a furring anchor and the method of installing the same for the attachment of a complementary frame structure, interior finish, light machinery or other devices.

In the present invention there is contemplated an anchor device which may be embedded in the concrete structure by being attached to the interior of the form and around which the concrete is poured while in fluid or plastic state, thereby insuring firm and secure embedment and interlocking engagement with the concrete body. The preferred form of anchor consists of a U-shaped insert preferably though not necessarily stamped from sheet metal, the upstanding arms of which are crimped, corrugated or of otherwise irregular outline to afford interlocking anchorage within the concrete body. The transverse interconnecting portion of the U-shaped insert is medially scored or weakened to enable it to be broken or separated subsequent to the embedment of the anchor, the wings or ears formed by such breakage or separation being adapted to be flexed outwardly into outstanding angular relation with the concrete body for engagement with the furring strip or other member to be attached. These attachment ears or extensions, initially interconnected, are perforated to receive nails from the interior, while in their interconnected initial relation, by which the anchor is temporarily attached to the concrete form. The same perforations are subsequently employed when the wings or ears are extended to receive nails for attachment of the furring strip or bolts or studs for the attachment for such other device or article, which it may be desirable to secure. In lieu of this construction, the attachment wings or ears may be initially disconnected but extended one toward the other in a common plane from the upstanding anchor arms, which may be permanently interconnected by a transverse tie as shown and described in my co-pending application, Serial No. 750,159 since matured into Patent No. 1,726,496.

The object of the invention is to simplify the structure as well as the means and mode

of installing such anchors, whereby they will not only be cheapened in construction, but will be more efficient in use, more securely and firmly embedded, durable, easily applied and unlikely to get out of order.

A further object of the invention is to provide an anchor member which may be secured in retracted form to the interior of the concrete mold or form, and later extended beyond the concrete body, subsequent to the removal of the form, thus enabling the anchors to be accurately located and firmly and securely embedded.

A further object of the invention is to provide such anchor, which may be quickly and accurately located by unskilled labor.

A further object of the invention is to enable the mounting of such anchors upon form boards, preliminary to the building of the concrete form, thus reducing construction costs and facilitating the accuracy with which such anchors may be located.

With the above primary and other incidental objects in view as will more fully appear in the specification, the invention consists of the features of construction, the parts and combinations thereof, and the mode of operation, or their equivalents as hereinafter described and set forth in the claims.

In the accompanying drawings, wherein is shown the preferred, but obviously not necessarily the only form of embodiment of the invention, Fig. 1 is a perspective view of the furring anchor forming the subject matter hereof, in its original or initial condition, preparatory to being located in the concrete form, the subsequent extension of the attachment wings or ears being indicated by dotted lines. Fig. 2 is a sectional view illustrating the application of the anchor to a concrete body, and to a furring strip secured thereto. Fig. 3 is a perspective view illustrating the assembly of the anchors upon a form board, preparatory to the building of the concrete form. Fig. 4 illustrates the anchor set in position in the concrete form, preparatory to pouring the mixture. Fig. 5 is an overhead perspective view of a section of concrete ceiling, showing therein a series of anchor members in successive stages of preparation.

Fig. 6 is a modification of the furring anchor as described and claimed in my co-pending application. Fig. 7 is a further modification employing a single anchor arm and wing.

5 Like parts are indicated by similar characters of reference throughout the several views.

In laying wooden floor upon a concrete foundation, or base, it is desirable to anchor or otherwise secure stringers or furring strips to such foundation, to which the flooring may be nailed. In the course of concrete building construction, it becomes necessary to apply furring strips to the side walls and to the 10 ceiling for supporting interior finish, attaching interior frame partitions, for supporting shelves or cupboards, and for attaching light machinery and the like, which it may be desirable to suspend from a ceiling or secure to 15 a side wall. The present anchor is adapted to be embedded in the concrete body while still in plastic state, with its attachment wings or ears in retracted relation, such attachment wings being extensible subsequent to the 20 removal of the concrete form. The anchor is illustrated in its simplest and preferred form in Figs. 1 to 4 of the drawings, wherein it consists of a single strip of sheet metal, bent into 25 rectangular U-shaped form, the upstanding arms 1-1 of which are corrugated or crimped to insure interlocking engagement or anchorage within the concrete body. The transverse interconnecting portion 2, of the anchor member is medially scored or weakened at 3, 30 to enable its subsequent breakage and separation of the lateral wing portions 4-4. Such medial scoring or weakening may be by means of an indentation extending substantially through the sheet material, or by a 35 succession of slits spaced one from the other, and separated by intermediate easily broken bridging portions. Any means which will enable the detachment of the lateral wings or attachment portions 4-4 one from the other may be employed. The wing portions 40 4-4 are perforated at 5 to receive nails 6, driven from the inside of the anchor member for temporarily securing it to the form board. As an inexpensive and rapid means of installation, a number of these anchor members 45 may be mounted upon separate form boards 7, in alignment with each other, preparatory to building the forms, as shown in Fig. 3. When assembled into a concrete form or 50 mold, such anchor members will extend within the mold as shown in Fig. 4, with the transverse connecting portion 2, comprising the attachment wings 4-4 abutting the face of the form, and the corrugated or crimped anchor arms 1 extending inwardly therefrom. It will be understood that in lieu of 55 the crimping or corrugations of the anchorage arms, such arms can be formed with 60 tongues, bosses, or other irregularities, which 65

will afford an interlocking engagement with the concrete body.

The anchor member being mounted within the form as shown in Fig. 4, the concrete material in fluid or plastic form is poured around the anchor embedding the arms 1-1 as shown in Fig. 2. The wing portion 4-4 of the interconnecting transverse portion 2, then lies in the plane of the surface of the concrete body, whether it be a wall or a ceiling. In the case of a concrete floor or foundation, the anchor members may be thrust into top surface of the concrete body while still in a plastic condition. The arms 1-1 are thrust into the mass until the transverse 70 portion 2 is flush with the surface of the concrete body. After the concrete has sufficiently set and hardened, the form boards are torn away, leaving the anchor member embedded in the hardened concrete body with the nails 6 from which the form boards have been detached protruding from the anchor members. The strain of removal or detachment of the form boards will ordinarily be sufficient to start or buckle the transverse connecting portion 2 of the anchor. This transverse portion is then broken by being pried outwardly, the line of breakage or separation being upon the medial score line 3, thus detaching the wings or ears 4-4 one from the other. 80 These wings are then bent outwardly to a position substantially at right angles to the face of the concrete body, as shown by dotted lines in Fig. 1, and as shown at *b* in Figs. 2 and 5. There is shown at *a* in Fig. 5, the anchor 85 member as disclosed upon the removal of the form board, and before being extended as shown at *b*. The furring strip, stringer or other structural member 9 is then interposed between the projected or extended wings 4-4 and is secured by nails 10, driven laterally into such stringer or furring strip, through the perforations 5 in a direction opposite to that in which the nails 6 were driven for attachment to the concrete form. It will be 90 noted that the construction enables the furring strip or stringer 9 to bear directly against the face of the concrete body throughout substantially its full length. The anchor thus enables a firm and extended bearing surface for the strip 9. By fixedly attaching the anchor arms 1-1 one with the other, preparatory to their embedment, and while being embedded in the concrete mixture, the proper spaced relation of the attachment wings or ears 4-4 when extended is insured. The anchor members are made in various sizes and widths to accommodate stringers or furring strips of different dimensions and also to afford anchors of greater or less strength, in accordance with the conditions of use, and the strain to which they are to be subjected. The method of installation as herein described is found to be an important factor in reducing construction 100 105 110 115 120 125 130 135

costs, and in insuring accuracy and perfect alignment of the anchor member for the reception of long furring strips. The anchor members may be placed in greater or less spaced relation according to conditions of use and the strain to which they are to be subjected. By medially scoring the connecting portion 2, the wings 4-4 are easily detached one from the other by prying with a small 10 bar or claw hammer, if indeed the detachment of the concrete forms does not itself break the wings 4-4 apart and partially flex them outwardly, after which it is only necessary to bend them to parallel relation 15 by a hammer blow.

In Fig. 6 is shown a modification wherein the extensible wing portions 4^a-4^a are normally and initially disconnected, one from the other, but are extended inwardly in a common plane. The anchor arms 1^a are interconnected by a transverse permanent connecting tie bar 11, which is formed integral with the wings 4^a and the anchor arms 1^a. Like the construction previously described, 25 this anchor is adapted to be embedded in the concrete body by being secured to the interior of the concrete form by nails being driven through the perforations of the wings 4^a. The concrete mass is poured about the anchor 1^a, and upon removal of the form boards the wings 4^a are flexed outwardly to extended position, as before described. In this construction the anchor arms are permanently interconnected by the transverse tie 11, even 35 after embedment in the concrete body, where- as as shown in Fig. 2, after separation of the attachment wings 4-4 the initially described construction, comprises two independent hangers embedded throughout a portion of 40 their length in the concrete body with the protruding portions attached to the opposite sides of the furring strip or stringer.

For conditions of use wherein the anchor is subjected only to minor strains, or for 45 attaching small strips, it may be desired to employ only one attachment wing or ear, in which case the unit may be broken into two L-shaped members before installation, or such single anchors may be initially produced in L-shaped form as shown in Fig. 7. Such single anchor is installed in the same manner by temporarily nailing the laterally projecting wing portion 4^b to the interior 50 of the form, and after removal of the form bending such wing outwardly as indicated by dotted lines in Fig. 7.

From the above description it will be apparent that there is thus provided a device 55 of the character described possessing the particular features of advantages before enumerated as desirable, but which obviously is susceptible of modification in its form, proportions, detail construction and arrangement of parts without departing from the

principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect and the invention is, therefore, claimed in any of its forms or modifications within the legitimate and valid scope of the appended claims.

Having thus described my invention, I claim:

1. As an article of manufacture, a furring anchor or the like for embedment in a concrete body comprising a substantially U-shaped unit, the arms of which are of irregular contour for anchorage purposes, the transverse connecting portion being perforated and separable upon an intermediate line of breakage to form two flexible attachment wings flexible outwardly for engagement with a furring strip or the like.

2. As an article of manufacture, an anchor unit to be embedded in a body of concrete, two initially interuniting wing portions, attachment means carried by the wing portion for anchorage engagement in the concrete body, said wings being adapted to be separated dividing the unit into independent sections and flexed outwardly for attachment to an extraneous body.

3. As an article of manufacture, anchor unit for concrete structures and the like, comprising a strip of sheet metal, the ends of which are upturned and corrugated, the intermediate portion of which is weakened on a medial line of breakage by the separation of which two outwardly flexible attachment wings are formed.

4. As an article of manufacture, an anchor unit for concrete structures and the like comprising a pair of anchor arms to be embedded in a body of plastic material, and an attachment wing flexibly attached to each anchor arm, said attachment wings being detachably united one with the other.

5. As an article of manufacture, two substantially L-shaped members, the lateral arms of which are temporarily interconnected, such arms being susceptible to separation and flexing into approximately parallel relation subsequent to the embedment of the initially upstanding parallel arms in a plastic body.

6. The herein described method of installing anchor inserts in concrete bodies consisting in attaching two spaced anchorage arms to a form side by an intermediate flexible connecting portion, depositing concrete thereabout, removing the forms, medially separating the intermediate connecting portion and

flexing the separated parts of the connecting portion outwardly beyond the face of the concrete body.

7. As an article of manufacture, an anchor unit or the like, including anchor portions to be embedded in a body of concrete and intermediate transverse portion connecting the anchor portions one with the other said transverse intermediate portion having perforations therein intermediate the anchor portions accessible from the back of the unit through which the unit may be nailed to a concrete form side preparatory to being embedded in the concrete deposit.

10 8. As an article of manufacture, an anchor unit or the like including a pair of corrugated spaced arms to be embedded in a body of concrete or the like, and a transverse perforated portion interconnecting the spaced arms, the perforations of said transverse connecting portion being exposed intermediate the corrugated arms enabling the unit to be nailed to the interior face of a concrete form through such perforations.

15 9. An anchor unit for attaching extraneous bodies to a concrete structure, including spaced anchor extensions to be embedded in the concrete body and an intermediate attachment portion detachably connecting the spaced anchor extensions one with the other, to insure proper spacing of the anchor extensions, the unit being divided into independent attachment members, by the separation of the intermediate attachment portion, which is adapted when disconnected to be flexed to angularly disposed portions in relation with the plane of the body for attachment to an extraneous body.

20 10. An anchoring device for floor sleepers placed upon concrete floors, comprising a pair of substantially L shaped angle sections of sheet metal disposed in substantial U form and means for detachably holding said angle sections together.

25 11. A sleeper anchor comprising a pair of angle members made of sheet metal held together in assembled condition and in substantial U form by an easily breakable connection, the legs of such U shaped member being adapted for insertion in wet concrete and the connected members of the U shaped structure limiting such insertion.

30 12. In a sleeper member comprising a pair of angle members made of sheet metal, means for detachably connecting the same together in substantial U form, the legs of such U shaped member being adapted for insertion in wet concrete and being constructed to resist removal, the connected members of the U shaped structure limiting such insertion.

35 13. An anchoring device for sleepers placed upon concrete floors, comprising a pair of single sections of sheet metal, said sections being held together by an easily breakable connection for insertion in the concrete as a

unit, each of said sections having a bendable portion arranged for disposal in vertical position after the connection has been broken and the concrete has set.

14. An anchoring device for sleepers 70 placed upon concrete floors, comprising a pair of substantially L shaped sheet metal angle sections disposed in substantial U form, and held in such assembled form for application as a unit by easily breakable means.

75 15. A sleeper anchor comprising angle members made of sheet metal held in assembled condition by an easily breakable connection, the legs of such anchor being adapted for insertion in wet concrete and having integral portions limiting such insertion.

80 16. As an article of manufacture, an anchor unit for insertion in a concrete body including anchor arms and attachment wings disposed in substantially right angle relation to the arms and connecting said arms in pairs, said wings being for attachment to the interior face of a form while the mass of material is being deposited thereabout, such attachment wings being subsequently extendable beyond the concrete body by flexing them outward from their approximately right angle relation with the anchor arms.

85 17. As an article of manufacture an anchor unit for insertion in a concrete body including anchor arms and attachment wings disposed in substantially right angle relation to the arms and detachably connecting the arms in pairs.

90 18. As an article of manufacture an anchor unit or the like including a pair of upstanding spaced arms to be embedded in a body of concrete, inturned attachment wings flexibly attached to said arms and extending thence 105 transversely in the direction of the opposite arm and detachably connecting said spaced arms one to the other, said inturned wings having therein perforations accessible between the upstanding spaced arms through which the unit may be nailed to the side of a concrete form.

100 In testimony whereof, I have hereunto set my hand this 5th day of April, A. D. 1924

105 CARL A. KINNINGER. 115
